Samuel H. Gibbs, of Albany New York.
assor to

Buck, and Wright, of St. Louis Missouri.
Letters Patent No 1741, dated March 24, 1863.

The schedule referred to in these Letters Patent and making part of the same

To all whom it may concern:

Be it known that I, Samuel H. Gibbs, of the City of Albany in the County of Albany and State of New York, have invented or produced a new and original design for the plates of a Parlor Stove, and I do hereby declare that the following is a full and exact description of the same.

The Stove is represented complete, and two views are given, one of the back and one of the front, Plate 1 giving view of the front and plate 2 that of the back.

What I claim as my invention, and desire to secure by letters patent is the design and configuration of the plates of a Parlor Stove as herein described and shown.
